UNITED STATES PATENT OFFICE.

PHILIP HISE, OF CINCINNATI, OHIO.

STIRRUP.

SPECIFICATION forming part of Letters Patent No. 435,932, dated September 9, 1890.

Application filed April 26, 1890. Serial No. 349,643. (No model.)

To all whom it may concern:

Be it known that I, PHILIP HISE, a citizen of the United States, residing at Cincinnati, in the county of Hamilton and State of Ohio, 5 have invented a new and useful Stirrup, of which the following is a specification.

The invention relates to improvements in stirrups.

The object of the present invention is to 10 simplify and improve the construction of stirrups and prevent the usual wear on the stirrup-strap, and thereby increase the strength and durability of the latter.

The invention consists in the construction 15 and novel combination and arrangement of parts hereinafter fully described, illustrated in the accompanying drawings, and pointed out in the claims hereto appended.

In the drawings, Figure 1 is a perspective 20 view of a stirrup constructed in accordance with this invention. Fig. 2 is a central vertical sectional view, the stirrup-block being shown in elevation. Fig. 3 is a detail view of the stirrup-block. Fig. 4 is a similar view 25 of one of the plates.

Referring to the accompanying drawings, 1 designates the sides of a stirrup constructed, preferably, of leather and having their lower 30 ends connected by a metallic foot-plate 2, provided at its ends with integral vertical flanges 3, that are riveted or similarly secured to the sides 1. The inner faces of the upper ends of the sides are provided with metallic plates 4, which are riveted to the 35 sides and have their inner faces recessed at 5, and are provided with slots or mouths 6, that have their inner or upper ends communicating with a circular opening 7. The plates 4 are adapted to be engaged by a metallic 40 stirrup-block 8, that has a rounded lower end 9 and converging side faces 10, and are provided at their ends with disks or heads 11, that are connected with the block by narrow neck portions 12 and are adapted to engage 45 the recesses 5 of the plate 4 and swivel the stirrup to a strap 13. The block is arranged horizontally to bring the necks 12 in alignment with the slots or mouths 6, and then the block can be moved vertically until the necks 50 engage the circular openings 7, which are sufficiently large to allow the necks to turn

freely therein, but are smaller than the disks or heads 11, and prevent the block being accidentally separated from the plates 4. The plates 4 and the foot-plate 2 may be secured 55 to any construction of stirrup, and the said plates 4 are adapted to swivel the stirrup to the stirrup-strap and enable the former to be readily turned to prevent the foot of the rider hanging in the stirrup. 60

From the foregoing it will readily be seen that stirrups constructed in accordance with this invention are exceedingly light, durable, and safe, and that the wear usually received by the stirrup-strap is confined to the swivel-block. 65

From the foregoing description and the accompanying drawings the construction, operation, and advantages of the invention will readily be understood. 70

What I claim is—

1. The combination, with the sides 1 and foot-plate 2, of the plates 4, having recesses 5 and slots 6, and the stirrup-block swiveled in the recesses and being removable therefrom and adapted to receive a strap, substantially as described. 75

2. The combination, with the sides 1 and the foot-plate 2, of the plates 4, having recesses 5 and provided with the slots 6 and having 80 the circular opening 7 and being removable therefrom, and the stirrup-block provided at its ends with the disks or heads 11 and the neck portions adapted to fit in the slots 6, and the opening 7, substantially as described. 85

3. The combination of the sides 1 and the foot-plate 2, the plates 4, having the recesses 5 and provided with the mouths or slots 6 and having the circular openings 7, and the removable stirrup-block having a rounded lower 90 end and converging side faces and provided at its side edges with the heads or disks 11 and the neck portions 12, substantially as described.

In testimony that I claim the foregoing as 95 my own I have hereto affixed my signature in presence of two witnesses.

PHILIP HISE.

Witnesses:

SAMUEL FORSYTHES,
J. M. HARRISON.
